UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

SEPARABLE FASTENER.

Application filed January 16, 1920. Serial No. 351,780.

To all whom it may concern:

Be it known that I, FRED S. CARR, a citizen of the United States, and a resident of Newton, in the county of Middlesex and 5 State of Massachusetts, have invented an Improvement in Separable Fasteners, of which the following description, in connection with the accompanying drawings, is a specification, like characters on the drawings representing like parts.

This invention pertains to improvements in separable fasteners, and means and methods of attaching the same to fabrics.

In the drawings, wherein I have shown a 15 preferred construction of one illustrative embodiment of my invention:—

Figure 1 is an elevation of two pieces of fabrics secured together by separable fasteners;

20 Fig. 2 is a plan view of a preferred form of socket;

Fig. 3 is a plan view of a preferred form of plate for securing the socket shown in Fig. 2 to the fabric;

25 Fig. 4 is a side elevation of the plate shown in Fig. 3;

Fig. 5 is a plan view showing the socket attached to the fabric by the attaching plate shown in Fig. 3;

30 Fig. 6 is a plan view of a preferred form of stud securing plate;

Fig. 7 is a plan view of a preferred form of stud prior to assembly;

Fig. 8 is a side elevation of the stud 35 shown in Fig. 7 prior to assembly;

Fig. 9 is a plan view showing the stud secured to the fabric by means of the stud-securing plate shown in Fig. 6;

40 Fig. 10 is a sectional elevation showing the stud and socket in engagement, the sections being taken on the line 10—10 of Fig. 1.

I will first describe the preferred form of socket and its attachment to the fabric. Referring to the drawings, I have shown a preferred form of socket including a spring-carrying casing providing at one side thereof a disc 18 having an aperture therein through which the head of the stud may pass, this 45 aperture preferably being notched at one side to provide a lateral lock in the general manner shown in my copending application, Serial No. 307,111, filed June 27, 1919, and the casing preferably containing a spring 50 55 19, which may be U-shaped as shown in said

application, and held in the casing by flanged-over marginal portions of the socket casing.

The preferred form of socket herein shown is adapted to be secured to the fabric without sewing, and preferably without perforation of the fabric by rivets, prongs or the like, such attachment being secured by squeezing the fabric under the rim of the socket casing by placing the socket casing 60 on one side of the fabric, placing the socket-attaching plate 20 shown in Fig. 3 on the opposite side of the fabric and pressing the two together so that the fabric is first 65 pressed into the opening in the socket casing and, as the socket-attaching plate 20 increases in diameter as it is flattened, forcing the fabric under the marginal lips of the socket casing.

I preferably utilize a tool in attaching the 70 socket and, where the preferred form of my invention shown in the drawings is utilized, I may conveniently use a pair of pliers assembled as shown in divisionals of this application Serial Nos. 601,832 and 601,833, 75 filed November 18, 1922.

I will now describe the attachment of the preferred form of stud. The stud-securing plate 24, shown in plan in Fig. 6, is preferably dished to provide a recess having 80 inwardly projecting marginal portions. The stud 25, best shown in Fig. 8, is preferably made with a conical base, slotted to permit increase in diameter thereof when flattened.

In securing the stud to the fabric, the 85 stud-securing plate 24 is preferably positioned on one side of the fabric with the stud 25 on the opposite side of the fabric, and the two are pressed together in such a way as initially to force the fabric into the opening in the stud-securing plate, and then, as the stud-securing plate and stud are pressed one towards the other and the stud expands, to provide for the carrying of the fabric beneath the flanged-over lips of the stud-securing plate.

100 This construction not only provides a very simple and effective method of securing the stud to the fabric, but preferably brings the neck of the stud approximately in line with the plane of the fabric to which the stud is secured, a feature which materially decreases the tendency of the stud to pull away from the socket when stud and socket are subjected to lateral strain.

It will be understood that I use the word "fabric" in its broader sense to include not only woven materials, but any flexible carrying medium.

5 While I have shown and described a preferred form of one embodiment of my invention, it will be understood that changes involving omission, substitution, alteration and reversal of parts, and even changes in 10 the mode of operation, may be made without departing from the scope of my invention, which is best defined in the following claims.

1. A stud for separable fasteners having an expansible base plate, and securing means 15 located on the opposite side of the fabric from the stud, the base of said stud expansible into engagement with said securing means, with the fabric to which the stud is to be engaged interposed between the base 20 of the stud and the securing means.

2. A stud for separable fasteners having a sloping base, said base split to permit an increase in the diameter of the base when flat, and a cooperating stud-securing element 25 providing a recess for receiving the periphery of the base of the stud when expanded, the fabric to which the stud is secured passing between said securing means and the periphery of said base.

30 3. A socket for separable fasteners including a casing having a flanged-over groove or rim, a spring held in said socket by said flanged-over rim, and means for securing said socket to its carrying fabric 35 and including an expansible part adapted to expand and press the carrying fabric beneath said flanged-over rim.

4. A separable fastener comprising, in combination, a stud and a socket, said socket

secured to the fabric by an expansible securing plate, said socket containing a spring and means on said socket and said socket-securing plate providing a predetermined relation therebetween to avoid interference with said spring by said socket-securing 45 plate.

5. A socket for separable fasteners having a dished plate providing a flanged rim, a spring held in said socket by said flanged rim and means for securing the socket to a 50 carrying fabric including an expansible plate adapted to expand and to crowd the carrying fabric beneath said flanged rim.

6. A socket for separable fasteners having a dished plate providing a flanged rim, 55 a spring held in said socket by said flanged rim and means for securing the socket to a carrying fabric including an expansible plate adapted to expand and to crowd the carrying fabric beneath said flanged rim at points 60 where said flanged rim does not overlie said spring.

7. In combination with a metallic secured separable fastener, a stud; a socket having a plate and a notched aperture therein, said notched aperture providing a lateral lock against separation of stud and socket by a resolution of forces arising from lateral strain in the general direction of the notch; and means for metallically securing the 70 socket to the fabric, said means insuring the positioning of the notch in adjacency to the edge of the fabric to which the socket is applied.

In testimony whereof, I have signed my 75 name to this specification.

FRED S. CARR.
